UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,126,030.

Specification of Letters Patent.

Patented Jan. 26, 1915.

Application filed November 29, 1913. Serial No. 803,688.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating 15 matrices are released from a magazine or magazines in the order in which their characters are to appear in print and then assembled in line, the composed line transferred to the face of a mold, the mold filled 20 with molten metal to form a slug or linotype against the matrices which produce the type characters thereon, and the matrices thereafter returned through distributing mechanism to the magazine or magazines 25 from which they started.

More particularly, it relates to that form thereof embodying a plurality of magazines, containing matrices of different style or font, any one of which may be brought 30 into action as desired.

In the accompanying drawings, I have shown my invention in preferred form and by way of example, and as applied to the commercial linotype machine, but obviously 35 many changes and variations may be made therein, and in its mode of application, which will still be comprised within its spirit. Thus, it may be applied to typographical machines or other kinds, such as 40 typesetters and typecasters, or those which handle type or dies, instead of matrices. Generally speaking, I desire it to be understood that I do not limit myself to any specific form or embodiment, except in so far 45 as such limitations are specified in the claims.

Referring to the drawings: Figure 1 is a front elevation, partly broken away, of a portion of a linotype machine having my 50 improvements embodied therein; Fig. 2 is an enlarged inside perspective of certain of the parts; Fig. 3 is a sectional detail of the escapements, etc.; Fig. 4 is an enlarged sec-

tion on the line 4—4 of Fig. 1; and Fig. 5 is a section on the line 5—5 of Fig. 4.

55

Referring to the drawings, a plurality of stationary superposed magazines A is illustrated, from which the matrices X are delivered as desired to the front plate F, from which in turn they pass to the other assembling devices, in the manner well understood in the art. The release of the matrices from the magazines is controlled by escapements (see Fig. 3), each comprising a pivoted lever B and pawls B¹, B², which are 60 alternately projected into the magazine channel. The spring B² tends to hold the rearward pawl B¹ in its projected or operative position, but this tendency is resisted and controlled by one of the projections C⁹ on the reed C⁷, which is normally pressed upward by a stronger spring, and is drawn downward by the keyboard mechanism upon the operation of the key C, all 65 in the manner set forth in my application 70 for Letters Patent hereinafter referred to. It will be noted that a single reed C⁷ is arranged to act on the correspondingly located escapements in each of the superposed magazines, in such manner that when it 75 is moved downward, all of the said escapements would be allowed to operate were it not for the additional mechanism next to be described.

Each of the magazines A is provided with 80 a transversely disposed rock shaft D, arranged in proximity to the inner ends of the escapement levers B and cut away or recessed to engage the same, as shown in Fig. 3, so that in one position of the rock 85 shaft, the escapement levers B are locked against movement by the springs B², and in another position thereof are free to be moved thereby, in the manner well understood in the art. It will be apparent, therefore, 90 that matrices may be delivered only from that magazine wherein the escapements are released from the locking influence of the rock shaft.

The rock shafts D are controlled respectively by pivoted operating levers E, one for each magazine, the inner end of each lever being connected by a link E¹ to a rock arm E² and connected hub E³, which in turn 95 engages with the corresponding rock shaft 100 D. A spring E¹⁰ connected to the outer end

of the lever E acts normally to move the rock shaft to its operative or locking position, this action being reversed by the movement of the lever E in the opposite direction.

5 My improvements also contemplate the interconnection and relation of the several magazines, so that when one is selected and brought into operation, the others will be held out of operation; that is to say, so that 10 when the escapements of one magazine are unlocked, the escapements of the other magazines will be locked. In the form shown, I obtain this object by a device acting upon and connecting the levers E, namely, the transversely movable plate J, which is normally urged to active position by the spring J¹. The plate J is constructed with a series of upwardly extending hooks 15 J², one for each lever E, and each hook is formed at its upper end with an inclined or beveled surface J³. When a lever is depressed, it moves the plate J laterally against the force of the spring J¹, by reason of its engagement with the beveled portion J³, after which the plate is restored by the spring and the lever is locked by the hook. When a second lever is then operated, it similarly shifts the plate J and thus 20 releases the previously actuated lever, after which the return movement of the plate in turn locks the second lever. It will thus be seen that the devices employed to interconnect the actuating levers, so that when one 25 is locked in position the others are automatically released, act indirectly to control the magazines, so that when one is selected and its escapements unlocked, the others are held out of action in that their escapements are 30 locked.

The parts so far described, in construction and mode of operation, are substantially similar to those disclosed in my application for Letters Patent, Serial No. 45 729,347, filed November 4, 1912, wherein they are designated by substantially the same letters of reference. In that arrangement the levers E were manually actuated by the operator, and it is one of the purposes of my present invention to obviate that necessity and to effect the selection of the magazines by power mechanism under the control of the operator, which arrangement also permits me to locate the controlling 50 keys in immediate proximity to the keyboard and within its field of action. To these ends, I preferably locate a series of key levers L, corresponding in number to that of the magazines, transversely of and 55 in immediate proximity to the keys C (see Fig. 1). The further end of the keys L are arranged to act upon the vertical slides L¹ (see Fig. 5), which in turn engage the sustaining pawls L², upon which normally rest 60 the free ends of the cam yokes M pivoted

at M². The cam yokes M carry the cams N adapted to engage the roll O, which may be conveniently formed as an extension of one of the actuating rolls of the keyboard mechanism. One of these cam yokes M is located 70 in immediate proximity to each of the previously mentioned levers E, and is provided with a stud M² to engage the lever, in such manner that when the cam yoke is tripped and its cam brought into engagement with the roll O, the cam yoke will be swung about its pivot and effect the operative movement of the lever E. This operation effects the turning of the corresponding rock shaft D and the consequent unlocking of the escapements of the selected magazine, and simultaneously the end of the lever E is brought 80 into engagement with one of the hooks J² of the plate J, after which the cam yoke returns to normal position. When another 85 key L is operated, the corresponding lever E is similarly actuated and locked, and the previously actuated lever E is freed from its hook J², all in the manner before set forth. 90

As previously stated, I have shown my invention only in preferred form and by way of example, and as applied to the specific mechanism illustrated, but obviously, many modifications and alterations therein, 95 and in its mode of application, will suggest themselves to those skilled in the art, without departure from its scope.

Having thus described my invention, its construction, and mode of operation, what I 100 claim and desire to secure by Letters Patent of the United States is as follows:

1. In a typographical machine, the combination of a plurality of magazines each provided with a locking device to retain the type or matrices therein, power-driven actuating means for each of said devices, and positive locking means to hold one of said actuating means in operated position, the said locking means being automatically 105 disengaged by the operation of another actuating means.

2. In a typographical machine, comprising a plurality of fonts of matrices, the combination of a plurality of power-driven devices to select one or another font, and positive locking means to hold one of said devices in operated position, the said locking means being automatically 115 disengaged by the operation of another selecting device. 120

3. In a typographical machine, the combination of a plurality of magazines each provided with a locking device to retain the type or matrices therein, power-driven actuating devices for moving the locking devices to their inactive position, locking mechanism to hold the actuating devices in their 125 operated position, and means whereby the operation of one of said actuating devices will automatically effect the release of the 130

locking mechanism and permit the return of a previously operated actuating device to its normal position.

4. In a typographical machine, the combination of a plurality of magazines each provided with a locking device to retain the type or matrices therein, power-driven actuating devices for moving the locking devices to their inactive position, locking mechanism to hold the said locking devices in their inactive position, and means whereby the movement of one of said locking devices to inactive position will automatically effect the release of the locking mechanism and permit the movement of a previously operated locking device to active position.

5. In a typographical machine, the combination of a plurality of magazines each provided with a locking device to retain the type or matrices therein, power-driven actuating devices for moving the locking devices to inactive position, mechanism for holding the locking devices in their inactive position, springs for moving the locking devices to their active position when released by the holding mechanism, and means whereby the movement of one of said locking devices to inactive position will automatically effect the release of a previously operated locking device and permit its movement to active position.

6. In a typographical machine, the combination of a plurality of magazines each provided with a locking device to retain the type or matrices therein, an actuating device connected to each of the locking devices, power-driven mechanism for operating the actuating devices, and positive locking mechanism for holding one or another of the actuating devices in its operated position, the said locking mechanism adapted to be disengaged automatically by the operation of a second actuating device.

7. In a typographical machine, the combination of a plurality of magazines each provided with a locking device to retain the type of matrices therein, a shiftable actuating device connected to each of the locking devices, power-driven mechanism for shifting the actuating devices, comprising a plurality of cam yokes, one for each actuating device, and positive locking mechanism for holding one or another of the actuating de-

vices in its shifted position, the said locking mechanism adapted to be disengaged automatically by the operation of a second actuating device.

8. In a typographical machine, the combination of a plurality of magazines each provided with a locking device to retain the type or matrices therein, a shiftable actuating device connected to each of the locking devices, power-driven mechanism for operating the actuating devices and comprising a plurality of cam yokes, one for each actuating device, finger keys for controlling the action of said cam yokes, and positive locking mechanism for holding one or another of the actuating devices in its shifted position, the said locking mechanism adapted to be disengaged automatically by the operation of a second actuating device.

9. In a typographical machine, the combination of a plurality of magazines each provided with a locking device to retain the type or matrices therein, a shiftable actuating device connected to each of the locking devices, power-driven mechanism for shifting the actuating devices comprising a plurality of cam yokes, one for each actuating device, mechanism for holding the actuating devices in their shifted position, springs for returning the actuating devices to their normal position when released by the holding mechanism, and means whereby the operation of one of said actuating devices will automatically effect the release of a previously operated actuating device and permit its return to normal position.

10. In a typographical machine, the combination of the plurality of magazines A each provided with the locking device D to retain the type or matrices therein, the actuating devices E¹, their operating levers E, power-driven mechanism comprising the cam yokes M for operating the levers E, and the locking plate J to hold the levers E in their operated position, the said plate adapted to be moved to unlocking position by the operation of a second lever E.

In testimony whereof I have affixed my signature in presence of two witnesses.
